UNITED STATES PATENT OFFICE.

CHARLES M. HUPP, OF PONCA CITY, OKLAHOMA.

DISPLAY DEVICE.

Application filed December 4, 1922. Serial No. 604,830.

To all whom it may concern:

Be it known that I, CHARLES M. HUPP, a citizen of the United States, residing at Ponca City, in the county of Kay and State of Oklahoma, have invented certain new and useful Improvements in Display Devices, of which the following is a specification.

This invention relates to display devices, and more particularly to a device adapted 10 to be attached to the radiator of a motor vehicle to display any desired matter, such as the city in which the owner of the vehicle resides.

An object of the invention is to provide a 15 device of this character that may be attached to the standard type of radiator cap or attached to a radiator provided with the usual form of temperature recording mechanism.

20 In the present invention, I provide a frame adapted to receive a strip of suitable material such as glass, bearing the matter to be displayed, and means for securing said frame to the radiator cap.

25 In the accompanying drawings, I have shown several embodiments of the invention. In this showing:

Figure 1 is a front elevation of one form of the invention with a temperature recording device attached thereto,

Figure 2 is a side elevation, parts being shown in section,

Figure 3 is a vertical sectional view on line 3—3 of Figure 1, the temperature recording device being shown in elevation,

Figure 4 is a detail sectional view on line 4—4 of Figure 3,

Figure 5 is a front elevation of another form of the invention,

40 Figure 6 is a vertical sectional view, and,

Figure 7 is a horizontal sectional view on line 7—7 of Figure 5.

Referring to the drawings, the reference numeral 1 designates the filling opening of 45 a radiator of a motor vehicle. This opening is adapted to receive a threaded cover 2 of the usual type. The threaded cover is provided with an opening for the reception of the stem of a temperature recording device. When the device forming the subject 50 matter of the present invention is applied to a motor vehicle, the temperature recording device is removed from the cap 2 and a threaded tube 3 placed therein. This tube 55 passes through a casing 4. As shown, the upper part of the tube is of larger diameter

than the smaller part forming a shoulder 5 which engages the casing to retain it on the support. The casing may be formed of any suitable material, preferably metal, and as shown, extends transversely of the vehicle. The front of the casing is open and is adapted to receive a plate 6, preferably formed of glass and is provided with suitable display matter 7 thereon. The opening in the casing is provided with ribs 8 to prevent inward movement of the glass plate and the plate is retained in position by means of retaining strips 9 arranged on the exterior.

As shown, the tube 3 extends through an opening in the top of the casing. The upper portion of the tube is provided with exterior threads 10 adapted to engage threads formed in the opening in the casing. This portion of the tube is also interiorly threaded for

the reception of the stem 11 of a temperature recording device 12. A lock nut 13 is arranged on the lower portion of the tube to retain the assembled device in position. When the device is employed without temperature recording mechanism, I prefer to use the construction shown in Figures 5 to

7 of the drawings. In this form of the invention, I provide a casing 14 having an opening therein to receive a plate 15. As shown, the plate is provided with suitable indicia extending vertically. The bottom

16 of the casing is provided with an opening for the reception of a bolt 17 adapted to project therefrom. The head 18 of the bolt is adapted to engage the interior of the bottom of the casing to retain the device in position. A lock nut 19 is arranged on the lower portion of the bolt, the bolt being adapted to be received in the opening

80 in the radiator cap 2, as in the form of the invention shown in Figures 1 to 4.

The operation of the device will be apparent from the foregoing description. The construction provides an attractive attachment for a motor vehicle by means of which the residence of the owner of the vehicle may be displayed. As shown, the device may be attached to the radiator cap of a motor vehicle and a temperature recording mechanism secured to the device without interfering with the functions of the temperature recording mechanism.

It is to be understood that the forms of my invention herewith shown and described 110 are to be taken as preferred examples of the same, and that various changes in the shape,

size, and arrangement of parts may be resorted to without departing from the spirit of the invention or the scope of the subjoined claims.

5 Having thus described my invention, I claim:

1. In a device of the character described, a casing having top and bottom openings in alinement with each other and having an

10 opening in one side, a display plate adapted to be received in said side opening, and a stem passing through said top and bottom openings and projecting below said casing, said stem being adapted to be received in

15 an opening in the radiator cap of a motor vehicle, the upper end of said stem being interiorly threaded for the reception of a temperature recording device.

2. In a device of the character described, 20 a casing, said casing being substantially rectangular in cross section, said casing be-

ing provided with top and bottom openings in alinement with each other and an opening in one side, a display plate arranged in said side opening, a threaded stem extending through the top and bottom openings of said casing, a portion of said stem being of reduced cross section, and forming a shoulder to engage the bottom of said casing, the upper end of said stem being interiorly 25 threaded to receive a temperature recording device, the lower end of said stem being exteriorly threaded and adapted to be received in an opening in the radiator cap of a motor vehicle, and a lock nut arranged 30 on the lower portion of said stem.

In testimony whereof, I affix my signature in presence of two witnesses.

CHARLES M. HUPP.

Witnesses:

JOHN W. WOLFE,
W. K. MOORE.
